UNITED STATES PATENT OFFICE.

EMORY STOCKWELL, OF STAMFORD, CONNECTICUT, ASSIGNOR TO THE
YALE & TOWNE MANUFACTURING COMPANY, OF SAME PLACE.

SAFE-LOCK.

SPECIFICATION forming part of Letters Patent No. 294,821, dated March 11, 1884.

Application filed January 2, 1884. (Model.)

To all whom it may concern:

Be it known that I, EMORY STOCKWELL, of Stamford, in the county of Fairfield and State of Connecticut, have invented certain new and 5 useful Improvements in Dial-Locks, of which the following is a specification, reference being had to the accompanying drawings, in which—

Figure 1 is a transverse section of a dial-lock 10 on the line 11 of Fig. 3. Fig. 2 is a section on the line 22 of Fig. 1. Fig. 3 is a section on the line 33 of Fig. 1. Fig. 4 is a section on the line 44 of Fig. 1. Fig. 5 is a section on the line 22 of Fig. 1, showing a formal modification; and 15 Fig. 6 is a similar section, showing another formal modification, in which one end bearing of the rotary fence-bearing is a hollow screw-cap.

The object of my invention is to produce a 20 dial-lock in which the ordinary rotating spindle and tumblers are used, and in which all the parts of the fence and bolt mechanism are rotary in their operation and are simple and compact in construction and arrangement with 25 respect to one another, whereby, at minimum cost of production, I secure certainty of operation and great durability without liability of the parts to get displaced. Thus I produce a lock in which all of the operative or moving 30 parts have rotary motion whenever the lock is operated, either for locking or unlocking. This enables me to attain the minimum of resistance and wear, and therefore the maximum of ease, certainty, and simplicity of movement.

One of the principal features of my improvements is a rotating bearing for a fence, which 35 may consist of either a solid or hollow cylinder, or of any other suitable form of rotating journal or bearing. Such a bearing obviates 40 the danger of "sticking" of the fence, as it is known in practice, which sometimes seriously interferes with the operations of locks of even the best types and most excellent workmanship, in which the fence-arbor is fixed. It 45 also adds greatly to the security of the lock against picking. I have shown such a rotating bearing in my United States patent for an improved dial-lock of even date herewith; but have not therein claimed it, broadly, nor do 50 I here, because I am aware that it is not new.

Referring now to the letters upon the drawings, A indicates a lock-case cast in one piece, including the tumbler curb-holder B, although the form or construction of the case is not material. C indicates the dial-spindle, D the 55 tumbler mechanism, E the rotary cam, and F the cap, all of ordinary construction.

G indicates the bolt-pivot, which is preferably removable, being a screw-bolt, as illustrated.

H indicates the rotary bolt, and I the rotary fence, which latter is provided with a balanced weight or wing, K, making it a balanced fence, although it need not necessarily be a balanced fence; but that is preferable. The bolt 65 and fence are each provided with segmental gears L, which connect them together in operative relations, as illustrated.

M indicates the rotary bearing of the fence, 70 on the lower end of which is a gear-wheel, N, meshing with a corresponding gear-wheel, O, on one face of the rotary cam, so that the rotation of the cam always causes the rotation of the rotary bearing of the fence.

In Fig. 2 I have shown the cylindrical bearing 75 of the fence, provided with a jointed shaft-bearing, P, one part of which is inserted in place, and afterward the other part, Q, which is provided with a screw-cap, is screwed to place, as well illustrated in Fig. 2. In Fig. 5, 80 however, I have shown the rotary fence-bearing as consisting of a hollow cylinder only, (which, however, might be a solid cylinder,) held in place by a screw-cap, Q. This cap should fit loosely upon the end of the rotary 85 bearing, so as not to interfere with its free rotation. In this instance the bearings of the rotary fence-bearing are directly in the sides of the lock-case, the screw-aperture R being of greater diameter than the bearing M, so as to 90 accommodate the setting of the bearing in its place in the lock, after which the cap Q is screwed to place.

R' indicates a raised block, which may be 95 and is preferably cast on the inside of the lock-case, to furnish a support for the bolt-pivot.

S is a ledge or projection, through or into which is formed the screw-threaded aperture 100 for the end of the bolt-pivot, and underneath

which is a recess, U, to accommodate the gear-wheel N. This construction enables the parts to be set very compactly in the case. V indicates a stop, which is shown as a bolt 5 or pin, but which might be any suitable stud or projection cast on the wall of the lock-case, to limit the rotary movement of the lock-bolt in the direction for unlocking. The operation of the cams and tumblers in their relation to the fence is as usual. This construction of lock is very convenient for both hand-changing and key-changing tumblers.

What I claim as new is—

1. In a lock, the combination of a rotary fence-bearing, a rotary fence, and a rotary bolt, operating together, substantially as set forth.
2. A lock-case provided with raised block R', having a ledge, S, with a bolt-pivot aperture, and a recess beneath, substantially as set forth.

3. In a lock, the combination of rotary tumblers and cam; a rotary fence and bolt connected operatively together, a rotary fence-bearing, and means for rotating the bearing 25 when the lock is operated, substantially as set forth.

4. In a dial-lock, the combination of a rotary fence-bearing, a spindle for operating the tumblers, and mechanism connecting or gearing the two together, so that whenever the spindle is rotated the fence-bearing must also rotate, substantially as described.

In testimony whereof I have hereunto subscribed my name this 29th day of December, 35 A. D. 1883.

EMORY STOCKWELL.
